CORE PUMP

Alfred C. Catland, Alhambra, Calif., assignor to
Globe Oil Tools Company, Los Nietos, Calif., a
corporation of California

Application August 21, 1934, Serial No. 740,797

6 Claims. (Cl. 103—38)

This invention relates to a pump and relates more particularly to a core pump useful in forcing cores of earth formation from the barrels of well tools, etc. A general object of the present invention is to provide a simple, practical core pump that is efficient under various operating conditions.

Core pumps are employed to pass fluid under pressure into the core barrels of core drills, etc. to force the cores therefrom. There are two general classes of core pumps now in use, namely single plunger pumps and double plunger pumps or compound pumps. The single plunger pumps that have been introduced are not entirely satisfactory because their rate of discharge or delivery is very low when high pressures are required to force a core from a barrel. The compound pumps or double plunger pumps are usually rather complex in their method of operation and are expensive.

Another object of this invention is to provide a core pump that embodies only a single plunger and is, therefore, simple in operation and inexpensive of manufacture, and that is capable of delivering fluid in desirable quantities at low pressures and is capable of delivering fluid at high pressures as conditions may require.

Another object of the invention is to provide a core pump in which the pivotal axis of the handle or operating lever may be readily shifted at will to adapt the pump to deliver fluid at a high rate and a relatively low pressure when the core moves freely in the barrel, or to adapt the pump for delivering fluid at a lower rate and at a higher pressure when the core is more tightly packed in the barrel.

Another object of the invention is to provide a core pump of the character mentioned that includes a novel particularly effective connection between the operating lever and the cross head of the plunger that does not require manipulation or adjustment when the pivotal axis of the operating lever is changed or moved.

A further object of the invention is to provide a core pump of the character mentioned that is simple and inexpensive of manufacture and easy and convenient to operate.

The various objects and features of this invention will be fully understood from the following detailed description of a typical preferred form and application of the invention, throughout which descriptive reference is made to the accompanying drawing, in which:

Fig. 1 is a side elevation of the pump of the present invention showing it in position to de-

liver fluid to a core barrel which has a portion broken away to show the core. Fig. 2 is an enlarged top or plan view of the pump. Fig. 3 is an enlarged fragmentary longitudinal detailed sectional view taken substantially as indicated by line 3—3 on Fig. 1. Fig. 4 is a fragmentary longitudinal detailed sectional view taken substantially as indicated by line 4—4 on Fig. 2. Fig. 5 is an enlarged transverse detailed sectional view of the valve means of the pump, being a view taken as indicated by line 5—5 on Fig. 1, and Fig. 6 is an enlarged longitudinal detailed sectional view of the operating lever, the mounting of the lever and the connection between the lever and the cross head, being a view taken as indicated by line 6—6 on Fig. 1.

The core pump of the present invention includes generally, a cylinder and plunger assembly 10, a handle or operating lever 11 adapted to be pivoted at spaced points and an operating connection 12 between the lever 11 and the plunger 20 of the assembly 10.

In accordance with the broader aspects of the invention the cylinder and plunger assembly 10 may be mounted or supported in any suitable manner. In the application of the invention disclosed in the drawing a base 13 serves to carry the assembly 10 as well as the other parts of the pump. The cylinder and plunger assembly 10 is preferably inclined or tilted as illustrated in Figs. 1 and 4 of the drawing. The cylinder 14 of the assembly 10 has its inner or lower end welded or otherwise attached to the base 13. A leg or support 15 extends from the upper portion of the cylinder 14 to the base 13 to support the outer or upper portion of the assembly 10 on the base. The assembly 10 includes a plunger 16 which enters the upper or outer end of the cylinder 14. Suitable packing means is provided for sealing about the plunger 16. In the particular construction illustrated the packing means includes packing 17 arranged in an annular recess in the cylinder 14 and a threaded gland 18 for compressing and holding the packing 17 in place.

The cylinder and plunger assembly 10 includes a valve means for controlling the intake and discharge of fluid from the cylinder 14. An enlargement or head 19 is provided on the lower end of the cylinder 14 and has an intake port 20 and a discharge port 21. The ports 20 and 21 communicate with the interior of the cylinder 14 at its lower end. The intake port 20 may terminate in an internally threaded boss 22 whereby the port 20 may be connected with a suitable source or supply of fluid (not shown). An in-

ternally threaded boss 23 may be provided at the outer end of the port 21. In the drawing I have shown a pipe 24 extending from the port 21 to a pressure head 25 applied to a core barrel B. A 5 pusher or piston P is slideable in the barrel B and is adapted to be acted on by fluid pressure from the pump to force the core C from the barrel B. A removable valve seat 26 is provided in the intake port 20 and a ball 27 is adapted to 10 seat outwardly against the seat 26, to prevent a reverse or outward flow through the port 20. A removable plug 28 normally closes an access opening to the port 20 and a spring 29 is arranged between the plug 28 and the ball 27 to 15 urge the ball to its closed position against the seat 26. A removable valve seat 30 is provided in the delivery or discharge port 21 and a ball 31 seats inwardly against the seat 30 to prevent a return flow into the cylinder from the pipe 24. 20 An access opening to the port 21 is closed by a removable plug 32. A spring 33 is arranged under compression between the inner side of the plug 32 and the ball 31 to urge the ball to its closed position on the seat 30. It is believed that 25 the operation of the valve means during the reciprocation of the plunger 16 will be readily understood.

The operating lever 11 is adapted to be manually pivoted or operated to actuate the plunger 16. It is a feature of the invention that the operating lever 11 is adapted to be pivoted at a plurality of spaced points to vary its mechanical advantage or leverage and thus vary the action of the pump. The operating lever 11 is preferably of rectangular cross section and is provided at its upper end with a suitable transverse handle or manually engageable rod 35. The lever 11 projects upwardly above the cylinder and plunger assembly 10 so that its handle 35 is 40 readily engaged for operation.

The means for pivotally supporting the lever 11 includes two spaced parallel members 36 extending upwardly from the base 13. The members 36 serve to support a guide for the cross 45 head of the plunger 13 as will be subsequently described. The lower ends of the members 36 are welded or otherwise attached to the base 13. In the preferred construction the members 36 are disposed at substantially right angles to the 50 inclined cylinder and plunger assembly 10. The operating lever 11 passes downwardly between the members 36 with substantial clearance. In accordance with the invention the members 36 are provided with series of longitudinally spaced 55 aligned openings 37. In the particular form of the invention illustrated in the drawing there are three pairs of horizontally aligned openings 37, it being understood that more sets or pairs of openings 37 may be provided if desired. The 60 lowermost set or pair of aligned openings 37 may be adjacent the base 13 while the uppermost pair of openings 37 may be adjacent the upper ends of the members 36. A transverse opening 38 is provided in the lower end portion of the 65 operating lever 11 and a removable pin 39 is adapted to be passed through any one of the pairs of openings 37 and the opening 38 to pivotally support the lever. A key 40 may be employed to removably lock the pin 39 in position. 70 and suitable washers or spacers 41 may be provided on the pin at the opposite sides of the lever 11. The spacers 41 may be welded or otherwise attached to the lever 11. It will be apparent that the removable pin 39 may be passed through 75 any one of the pairs of openings 37 and through

the opening 38 of the lever to pivotally support the lever at any one of the three spaced points to change the leverage of the lever and the operation of the pump.

The connection 12 between the operating lever 5 11 and the plunger 16 includes a cross head 42 on the projecting outer end of the plunger 16. A guide 43 extends longitudinally from the outer end of the cylinder 14 to slidably support and guide the cross head 42. The members 36 described above have their upper ends attached to the guide 43 and aid in supporting the guide. Longitudinal slots 44 are provided in the upper and lower sides of the guide 43 and the operating lever 11 passes upwardly through the slots 15 44 to project above the guide. The cross head 42 of the plunger is yoked, being provided with two spaced arms 45. A bearing or block 46 is disposed between the arms 45. Pins 47 project from the arms 45 into openings 48 in the block 20 46 to pivotally support the block in the cross head. An opening 49 in the block 46 slidably or shiftably passes the operating lever 11. The opening 49 preferably corresponds in transverse cross section to the operating lever 11. Pivoting or oscillation of the lever 11 is transmitted to the plunger 16 through the medium of the block 46 and pins 47 so that the plunger is reciprocated when the lever is pivoted back and forth. The connection between the operating lever 11 30 and the cross head 42 allows the operating lever 11 to be readily shifted or moved longitudinally without disturbing the plunger, the cross head or any of the other parts.

In employing the core pump of the present invention a pipe 24 may extend from the discharge port 21 to the end of the barrel B so that the pump may pass a suitable liquid under pressure into the barrel. A pipe, (not shown) may conduct the liquid from a suitable source to the intake port 20. Pivoting of the lever 11 back and forth of course results in reciprocation of the plunger 16. As the plunger 16 is reciprocated the liquid is alternately drawn in through the port 20 and discharged through the port 21. The liquid under pressure admitted into the end of the barrel B forces the pusher or piston P through the barrel to force the core from the outer end of the barrel. In accordance with the invention the pump may be easily and quickly modified or adjusted to efficiently force cores from the barrels when the cores move freely in the barrels or when the cores are tightly packed in the barrels. The operating lever 11 may have its lower end pivotally supported in any one of the spaced 50 positions to change the mechanical advantage of the lever and the discharge rate of the pump.

When the operating lever 11 is pivotally supported at its lowermost position, as illustrated in Fig. 6 of the drawing, the lever has the least 60 mechanical advantage, but its operation provides for the largest discharge rate from the port 21. The operating lever 11 may be supported in its lowest position when the core C is quite easily moved in the barrel and does not require a great force to move it out of the barrel. The high discharge rate of the pump when the lever 11 is pivoted at its lowest position provides for the rapid forcing of the core C from the barrel B. When the core C is more tightly set or packed in the barrel and a higher fluid pressure is required to force it through the barrel the pin 39 may be removed and the lever 11 raised to a position where the pin 39 may be passed through either the intermediate or the highest pair of openings 70 75 75

37 to support the lever in its intermediate or highest position. With the lever 11 in its intermediate position its operation causes the pump to deliver liquid to the barrel B at a medium rate 5 and at a medium pressure. When an extremely high fluid pressure is required to force the core C from the barrel B the pin 39 may be employed to pivotally support the lever 11 in its highest position where the pin extends through the uppermost pair of openings 37. The operation or pivoting of the lever 11 when it is in its highest or uppermost position actuates the pump to deliver liquid under a high pressure but at a reduced rate. The liquid under the high pressure 10 admitted to the end of the barrel B drives the piston P and the core C through the barrel.

It is to be particularly noted that the slideable pivotal connection 12 between the lever 11 and the cross head 42 provides for the necessary relative movement between the lever and cross head during the operation of the pump and allows for the ready longitudinal adjustment of the lever 11 between its various positions. The lever 11 in being slideable in the opening 49 may be shifted 20 longitudinally when it is to be pivotally supported at the different positions without requiring the manipulation or adjustment of the connection 12, the cross head 42 or the plunger 16. The core pump embodying the means for pivotally supporting the operating lever at spaced points and the slideable pivotal connection between the operating lever and the plunger 16 is readily adaptable to various operating conditions.

Having described only a typical preferred form 35 and application of my invention, I do not wish to be limited or restricted to the specific form and application herein set forth, but wish to reserve to myself any modifications or variations that may appear to those skilled in the art or 40 fall within the scope of the following claims.

Having described my invention, I claim:

1. Mechanism for operating a core pump having a plunger including a lever for operating the plunger, a fixed support having openings spaced 45 different distances from the axis of movement of the plunger, a removable pin adapted to be inserted in the openings to pivotably connect the lever to the support at any one of a plurality of spaced points, and means pivotably and shiftably connecting the lever with the plunger whereby the lever may be adjusted longitudinally to operate the plunger when pivoted at any one of said 50 points, the last named means including a bearing pivotably connected with the plunger and having an opening shiftably passing the lever.

2. In a core pump having a reciprocable element, means for operating the element including a cross head on the element, an operating lever, a relatively fixed support, means for pivoting the lever to the support at any one of a plurality 55 of definite points spaced different distances from

the axis of movement of the cross head, and a block pivoted to the cross head having an opening shiftably passing the lever whereby the lever may be adjusted longitudinally, and a guide for the cross head carried by the support and arranged parallel with the said element. 5

3. In a core pump, a base, an inclined cylinder having its lower end supported on the base, a guide extending longitudinally from the upper end of the cylinder, a support extending upwardly from the base and carrying the guide, a plunger operable in the cylinder, a cross head on the plunger slidably carried by the guide, an operating lever pivotally and shiftably connected with the cross head, and means for pivotally connecting the lever with the support at any of a plurality of points spaced longitudinally of the support whereby the stroke of the plunger may be changed. 10

4. In a core pump, a base, an inclined cylinder having its lower end supported on the base, a guide extending longitudinally from the upper end of the cylinder, a support extending upwardly from the base and carrying the guide, a plunger operable in the cylinder, a cross head 25 on the plunger slidably carried by the guide, an operating lever pivotally and shiftably connected with the cross head, there being longitudinally spaced openings in the support, and a pin adapted to be entered in any of the openings to pivotally connect the lever with the support at any one of a plurality of longitudinally spaced points. 30

5. A core pump including a base, an inclined cylinder having its lower end supported on the base, spaced guides projecting longitudinally 35 from the upper end of the inclined cylinder, a plunger operable in the cylinder, a cross head on the plunger carried by the guides, a support extending upwardly from the base and carrying the guides, the support having vertically spaced 40 openings, an operating lever extending vertically between the guides, and projecting upwardly therefrom for manual actuation, means pivotably and shiftably connecting the lever with the cross head, and a pin adapted to be introduced 45 into any one of the openings to pivotably connect the lever with the support.

6. In a core pump having a plunger, an operating means including a lever, means for pivotably supporting the lever at any one of several 50 points spaced different distances from the axis of movement of the plunger, and means operatively and shiftably connecting the lever with the plunger to allow longitudinal adjusting of the lever, the last named means including a yoke on 55 the plunger, and a block pivoted in the yoke having an opening slidably passing the lever, and guides in parallel relation to the plunger slidably guiding the yoke and spaced apart so that the lever may extend therebetween. 60

ALFRED C. CATLAND.
